UNITED STATES PATENT OFFICE.

PERCY MORRIS, OF LONDON, ENGLAND.

COLOR-PRINTING MACHINE.

1,243,333.

Specification of Letters Patent. Patented Oct. 16, 1917.

Application filed March 15, 1916. Serial No. 84,424.

To all whom it may concern:

Be it known that I, PERCY MORRIS, a subject of the King of Great Britain, residing at 9 and 10 Fenchurch street, London, England, have invented new and useful Improvements in Color-Printing Machines, of which the following is a specification.

This invention relates to improvements in apparatus for multi-color or polychrome printing, and especially for printing or producing a texture ground-work for bank notes, bonds and other securities which considerably adds to the security of such notes or for other purposes where extreme perfection in registration is required.

If an ordinary polychrome print be examined under a magnifying glass it will be found that the registration of the colors is only approximate. Accurate registration for ordinary pictorial effects is not necessary.

If a texture has to be printed, it is very essential that the registration for the successive printings should be extremely accurate so that the individual elements may exactly fit into their proper positions and the relative configuration be exactly the same in each copy.

For example, the characteristic appearance of the texture will depend upon the sizes, shapes and relative configuration of the individual elements. An extremely small variation of these factors may very well result in a texture having a different appearance.

The object of the present invention is to provide for cases in which exceedingly accurate register is necessary and in which the register determines the characteristic appearance of the print, and the invention consists in employing in combination with a series of printing surfaces designed to be successively brought into printing position an arrangement of magnets which will draw frames carrying the printing surfaces into close contact with accurately adjusted stops.

A suitable form of printing machine in which my invention can be carried into practice comprises a series of printing blocks or surfaces arranged upon a sliding carrier in conjunction with an oscillating plunger, the said carrier being adapted to be moved intermittently with relation to the said plunger in such a manner that each oscillation of the said plunger will trans-

fer a printing block from the carrier to make an impression and then return it to the carrier.

To enable my invention to be fully understood I will describe it with reference to the accompanying drawings, in which:—

Figure 1 is a front elevation of such apparatus wherein the printing blocks are successively brought into operative position with a fixed plunger having thereon the paper to be printed.

Fig. 2 is a sectional side elevation.

Fig. 3 is a sectional side elevation of a part of the mechanism detached.

Fig. 4 is a front view of a printing frame detached and drawn to a larger scale than Fig. 1, and

Fig. 5 is a side view of the same.

a indicates the oscillating plunger which carries the printing block and *b* the platen upon, or against, which the paper to be printed lies, the said plunger *a* being mounted upon a framing *c* which at the upper part also carries the platen *b*, side frames *c*, *c* connected to the said framing serving to carry the inking table *d* in connection with which the inking rollers *e*, *e* operate in a manner which will be readily understood. The duct *e* containing the ink is divided into sections for the different colors and the rollers *e* also divided in lengths to keep the colors from overlapping.

Between the frames *c* I arrange a transverse guide *f* upon which is mounted a slide or carriage *g* having depending from it a series of horns *h*, *h* upon which frames *i*, carrying the printing blocks, are designed to be supported and moved in a transverse direction with relation to the printing surface. Each of these frames, one of which is shown detached in Fig. 4 and drawn to a larger scale than the other figures, is, as shown, designed for carrying two printing blocks so that two impressions may be made at the same time, but it is to be understood that the frames may be adapted for carrying one or more printing blocks.

Each printing frame or chase has upon its lateral edges flanges *k*, *k* which are designed to rest upon lugs *k* at the lower end of the horns *h*, as clearly indicated in Figs. 1, 2 and 3.

The slide *g* is designed to have an intermittent movement imparted to it, in one direction, for the purpose of bringing the several printing frames successively into po-

sition between the oscillating plunger *a* and the platen *b*, and, as shown in the drawings, this is effected through the medium of a pawl *l*, Fig. 1, engaging with teeth *l*⁰ on the slide *g* and carried at the extremity of a lever arm *l*¹ (see Fig. 1) oscillated through the medium of a rod *l*² by a crank *l*³ on a shaft *l*⁴ driven by gearing *l*⁵ from the main shaft *m*, the gearing being put into and out of gear to obtain an accurate timing of the said lever by means of a clutch *l*⁶.

As a series of printing frames *i*, each designed for printing a separate color, is employed, it is obvious that each frame is only 15 temporarily in contact with the oscillating arm *a*, the arrangement being such that, as the machine operates, the printing frame which lies between the head of the said oscillating plunger and the platen *b* shall be 20 taken off the carrier and moved up to the printing bed to make an impression, and then be brought back by the said oscillating plunger and replaced upon the slide or carriage *g*, whereupon the said slide will be 25 moved another step to bring the next frame, for printing another color, into position, when the operation will be repeated, and so on.

A series of micrometer screws *i*² is 30 provided for registering the blocks *i*¹ in their respective frames *i*, and a series of stops *n*, *n*, *n*¹ preferably adjustable, is also provided for automatically positioning the frames *i*, the stops *n* serving for the vertical adjustment of the printing frames *i* and the stop *n*¹ for the lateral adjustment thereof. The printing frames *i* are brought 35 into contact with these stops immediately prior to the printing operation by a magnet, and advantageously an electromagnet *n*² is provided for insuring the close contact of the frames with the lateral stop, the said magnet being fixed on the frame *c* in proximity to the platen *b*.

45 A rotary switch or other electrical contact device, not shown, is provided at some suitable part of the mechanism for energizing the magnet coils at the required moment before the printing block is pressed into contact with the surface to be printed so as to insure that the printing frame is in close contact with the respective stops.

In practice it will probably be found, with the particular form of mechanism shown, that the weight of the printing frame will be sufficient to insure proper contact with the stops *n*, *n*, but, if desired, a magnet *o* may be arranged adjacent to the lower part of such frame for exerting a pulling action, the said magnet being supported on the frame *c*.

60 In order to support the printing frames *i* upon the oscillating plunger *a* during the time they are unsupported by the carrier slide *g*, the said carrying plunger *a* is pro-

vided with a shelf *p* which passes beneath the bottom of each printing frame before it is moved off the said carrier *g* and the portions of the frames *i* which make contact with the stops *n*, *n*, *n*¹ are beveled or inclined, as shown in Figs. 4 and 5, to bring the said frames accurately into position.

When the oscillating plunger *a* has been operated, (say by a cam *q* carried on a shaft *q*¹ geared by gear wheels *q*², *q*³ with the main shaft *m*) to cause the printing block to make an impression, the said oscillating plunger will commence its rearward movement, the printing frame *i* remaining supported upon the shelf *p* of such plunger until the latter has moved back far enough for the lugs *h*¹ on the carrier, to engage beneath the flanges *h* of the said frame. If the weight of the form or chase is not sufficient to allow it to return with perfect safety to the oscillating plunger after printing one or more electro-magnets may be employed to attract the chase or block, the said magnet or magnets being in this case attached to or embedded in the bed of the said plunger. The said frame is then moved a step farther to bring another frame *i* into position and so on. The gear wheel *q*³ is attached to the gear wheel *l*⁵ so that they are simultaneously put into gear by the clutch *l*⁶.

After the carrier slide *g* has been moved to take an impression from all the blocks (the extreme position of such carrier being indicated by dot and dash lines in Fig. 1) it is necessary to return the said carrier frame to the position indicated in full lines in the said figure, and this is advantageously accomplished by means of mechanism which is most clearly shown in Fig. 3 of the drawing and which comprises a bevel wheel *r* which receives its motion through spur gearing *r*¹ from the main shaft *m* through the medium of a clutch *r*², a bevel pinion *r*³ upon one end of a shaft *r*⁴ and gearing with the wheel *r* which shaft carries at the other end one of a pair of bevel wheels *r*⁵, the other of which is on a shaft *r*⁶ carrying a toothed pinion *r*⁷ engaging with a rack *r*⁸ on the back of the slide. As, however, the return movement of the slide would cause the pawl *l* to foul the teeth *l*⁰ on the said slide I provide means for holding the pawl slightly elevated during such return movement. For this purpose the pawl operating gear is timed to move the pawl on its backward movement a short distance only along an incline *l*⁹ at the right hand end of the slide, a pin *l*⁸ on the pawl riding past and lifting a pivoted gravity switch *l*¹⁰ so that when the slide *g* commences the return movement the said pin *l*⁸ will ride up on to a shelf *l*¹¹ on the slide on which it will be supported to hold the pawl out of the path of the teeth *l*⁰ until the slide *g* nearly 130

finishes its return movement when the pawl will no longer be supported by the shelf and fall to its normal position, so that when the pawl is allowed to complete its backward movement it will engage behind the first tooth t^o .

5 c^2 is a standard or frame to assist in supporting the slide g when moved out of the guide f into the dotted line position indicated in Fig. 1.

10 The pinion r^3 may be connected to its shaft in such a way as to constitute a free wheel when rotating during the time that the slide g is being actuated to bring each 15 printing frame i successively into the printing position.

15 The inking rollers e, e are spring connected to arms e^1 in the known way, the said arms being supported upon a shaft e^2 designed to be oscillated through the medium 20 of an arm e^3 thereon, a connecting rod e^4 and a crank e^5 loose on the shaft m but designed to be engaged therewith by a clutch e^6 . The inking rollers are timed to be actuated when the slide g has been returned 25 to the position shown in Fig. 1.

30 In the arrangement shown the printing surface will always recline upon the oscillating plunger, and it is therefore necessary that the printed surface should be similarly inclined, this renders difficult the use of 35 separate sheets. We have, therefore, in the drawing shown the printing as being effected upon a web of paper s carried on a roll r and then intermittently moved over the printing platen by the feed rolls u . In connection with these feed rolls I have shown a knife v for successively severing the printed sections from the web s .

40 For bringing the various mechanisms of the machine into and out of gear at the required time suitable timing gear, not shown, is employed.

45 It is to be understood that my invention is not in any way limited to the arrangement of mechanism described as it will be obvious that the printing frames can be moved into and out of printing position by means other than those described. Also, it is to be understood that instead of employing printing surfaces designed to be successively brought into position to print upon a stationary surface as hereinbefore described, I 50 may arrange the printing surfaces to be stationary while the surface to be printed is moved successively into accurately registered positions determined by rigid abutments.

55 It will further be understood that the magnets for pulling the frame into position may be quite independent of the parts carrying the stops against which the registration is effected.

Claims:

60 1. In a printing machine, a platen for sta-

tionarily supporting the material to be acted upon while a plurality of impressions are made, a plunger coöperating with said platen, a carrier movable relative to the platen, a plurality of printing blocks removably supported by said carrier and adapted to be brought successively into position to make an impression upon the material, and means provided on said plunger for detaching the blocks from said carrier and temporarily supporting said blocks while they are being applied to the material.

2. A printing machine comprising a platen for stationarily supporting the material to be acted upon while a plurality of impressions are made, a plunger coöperating with said platen, a carrier movable relative to the platen, a plurality of printing blocks removably supported by said carrier and adapted to be brought successively into position to make an impression upon said material, means for applying differently colored inks to said blocks, and means provided on said plunger for detaching the blocks from said carrier and temporarily supporting said blocks while they are being applied to the material.

3. In a printing machine, a platen for stationarily supporting relative to the platen, the material to be acted upon while a plurality of impressions are being made, a plunger coöperating with said platen, a carrier, a plurality of printing blocks removably supported by said carrier and adapted to successively make an impression upon said material, and means provided on said plunger for detaching the blocks from said carrier and temporarily supporting said blocks while they are being applied to the material.

4. In a printing machine, a platen for stationarily supporting the material to be acted upon while a plurality of impressions are being made, a plunger coöperating with said platen, a carrier horizontally movable relative to the platen and provided with projecting arms, a plurality of printing blocks removably supported by said carrier and adapted to successively make an impression upon said material, and means provided on said plunger for detaching the blocks from said carrier and temporarily supporting said blocks while they are being applied to the material.

5. In a printing machine, a platen for stationarily supporting the material to be acted upon while a plurality of impressions are made, a plunger coöperating with said platen, a carrier movable relative to the platen, a carrier movable relative to the platen and provided with depending arms having supporting lugs, a plurality of printing block frames removably supported by said lugs and each carrying a plurality of printing blocks, the printing blocks of each

- frame being adapted to be brought successively into position to make an impression upon the material, and means provided on said plunger for detaching the block frames 5 from said jugs and temporarily supporting the same while the blocks are being applied to the material.
6. In a printing machine, a platen for stationarily supporting the material to be acted upon while a plurality of impressions are made, a plunger coöperating with said platen, a carrier movable relative to the platen, means for intermittently moving said carrier, a plurality of printing blocks 15 removably supported by said carrier and adapted to be brought successively into position to make an impression upon the material, and means provided on said plunger for detaching the blocks from said carrier 20 and temporarily supporting said blocks while they are being applied to the material.
7. In a printing machine, a platen for stationarily supporting the material to be acted upon while a plurality of impressions are made, a plunger coöperating with said platen, a carrier movable relative to the platen, a plurality of printing blocks 25 removably supported by said carrier and adapted to be brought successively into position to make an impression upon the material; means provided on said plunger for detaching the blocks from said carrier and temporarily supporting said blocks while they are being applied to the material, and 30 independent registering means for insuring accurate registration of the blocks with the material.
8. In a printing machine, a platen member for supporting the material to be acted upon, a plunger movable toward and away from said platen, a frame member carrying a printing block movably supported by said plunger, stops provided upon one of said members, and inclined surfaces provided on 45 the other member, said stops being adapted to engage the inclined surfaces as the plunger moves toward said platen.
9. In a printing machine, a platen member for supporting the material to be acted upon, a plunger movable toward and away from said platen, a frame member carrying a printing block movably supported by said 50
- plunger; stops provided upon one of said members, inclined surfaces provided on the other member designed to engage said stops 55 when the plunger approaches the platen, and a magnet provided on one of the members and adapted to draw the other member toward the same before an impression is made. 60
10. In a printing machine, the combination with a platen member and a printing block frame member supporting a printing block which coöperates with said platen member, of electro-magnets provided on one 65 of said members and adapted to draw the other member toward the same before an impression is made.
11. In a printing machine, a platen provided with stops, a plunger coöperating with said platen, a printing block frame movably supported by said plunger and provided with inclined surfaces adapted to engage said stops when the plunger is moved toward said platen, and electro-magnets for 70 drawing said frame toward said stops. 75
12. In a printing machine, a platen provided with adjustable stops, a plunger coöperating with said platen, a printing block frame movably supported by said plunger and provided with inclined surfaces adapted to engage said stops when the plunger is moved toward said platen, and electro-magnets for drawing said frame toward said stops. 80 85
13. In a printing machine, a platen provided with adjustable stops, a plunger coöperating with said platen, a carrier horizontally movable relative to the platen, a printing block frame removably supported by said carrier and provided with inclined surfaces adapted to engage said stops when the block frame is moved toward said platen, means provided on said plunger for detaching the frame from the carrier and temporarily supporting the same while said block is being applied to the material acted upon, and electro-magnets for drawing said frame toward said stops. 90 95
